UNITED STATES PATENT OFFICE.

ALBERT BISHOP CHANCE, OF CENTRALIA, MISSOURI.

ARRESTER.

No. 894,723.

Specification of Letters Patent.

Patented July 28, 1908.

Application filed September 12, 1906. Serial No. 334,342.

To all whom it may concern:

Be it known that I, ALBERT BISHOP CHANCE, a citizen of the United States, residing at Centralia, in the county of Boone and State of Missouri, have invented new and useful Improvements in Arresters, of which the following is a specification.

This invention relates to lightning arresters, and it has for its object to simplify and improve the construction of the same.

With these and other ends in view which will readily appear as the nature of the invention is better understood, the same consists in the improved construction and novel arrangement and combination of parts which will be hereinafter fully described and particularly pointed out in the claim.

In the drawings: Figure 1 is a side elevation of a lightning arrester constructed in accordance with the principles of the invention. Fig. 2 is a longitudinal sectional view of the same. Fig. 3 is a transverse sectional view taken on the plane indicated by the line 3-3 in Fig. 2.

Corresponding parts in the several figures are denoted by like characters of reference.

The improved lightning arrester comprises in its construction a tubular body 1 of porcelain or other suitable non-conducting material; upon the ends of said tubular body there are fitted heads 2, 2, likewise constructed of porcelain or similar non-conducting material; said heads being provided with recesses 3 for engagement with the ends of the tubular body. The heads 2, 2 are provided with exterior shoulders 4 for engagement with the ends of the tubular metallic casing 5, and the heads are also provided with longitudinal apertures 6 for the passage of the ends of a wire coil 7 which is wound upon the

body 1 within the casing 5. The parts are assembled by a bolt or rod 8 extending through the tubular body 1 and through central alining apertures 9 in the heads 2, 2; the latter being provided with countersinks 10 for the reception of the bolt-head 11 and the nut 12. The tubular metallic casing 5 is provided with a boss 13 having a threaded aperture for the reception of a screw 14 constituting a binding post whereby the metallic casing 5 is connected with the ground wire 15.

When the lightning arrester has been properly installed currents of excessive potential will break across the gap between the coil 7 and the casing 5 and passed to ground through the conductor 15.

Having thus described the invention what is claimed is:

The herein described lightning arrester, consisting of a longitudinally bored non-conducting body, non-conducting heads fitted upon the ends of said body, and provided with countersunk ends, said heads having longitudinal apertures therein, and external shoulders thereon, a tubular metallic casing inclosing the non-conducting body and engaging the shoulders of the heads, a headed bolt passing through the non-conducting body and heads and secured to said heads by a nut on one end thereof, a wire extending through the heads and coiled around the non-conducting body, and a ground wire connected to the tubular casing by a binding screw, substantially as specified.

In testimony whereof, I affix my signature in presence of two witnesses.

A. BISHOP CHANCE.
